DESIGN FOR A TEXTILE FABRIC

John H. Abt, New York, N. Y., assignor to Deering
Milliken & Co., Inc., New York, N. Y., a corporation of New York

Application April 25, 1942, Serial No. 106,707

Term of patent 3½ years

To all whom it may concern:

Be it known that I, John Abt, a citizen of no country, but have declared my intentions of becoming a citizen of the United States of America, residing in the city of New York, county of New York, and State of New York, have invented a new, original, and ornamental Design for a Textile Fabric, of which the following is a specification, reference being had to the accompanying drawing, forming part thereof, wherein,

The figure of the drawing is a plan view of a textile fabric showing my new design.

I claim:

The ornamental design for a textile fabric, substantially as shown.

JOHN H. ABT.
